(57) **CLAIM**

The ornamental design for an endoscope handle, as shown and described.

DESCRIPTION

FIG. 1 is a front, right, perspective view showing my new design;

FIG. 2 is a back, left perspective view thereof;

FIG. 3 is a right side view thereof;

FIG. 4 is a back side view thereof;

FIG. 5 is a left side view thereof;

FIG. 6 is a front view thereof;

FIG. 7 is a top view thereof; and,

FIG. 8 is a bottom view thereof.

The broken lines illustrate portions of the endoscope handle and form no part of the claimed design.

1 Claim, 7 Drawing Sheets
